G. V. Sheffield.
Steam-Generator.

N° 72689

Patented Dec. 24, 1867.

Inventor:

George D Sheffield

United States Patent Office.

GEORGE V. SHEFFIELD, OF WORCESTER, MASSACHUSETTS.

Letters Patent No. 72,689, dated December 24, 1867.

IMPROVEMENT IN STEAM-GENERATORS.

The Schedule referred to in these Letters Patent and making part of the same.

KNOW ALL MEN BY THESE PRESENTS:

That I, GEORGE V. SHEFFIELD, of the city and county of Worcester, and Commonwealth of Massachusetts, have invented certain new and useful Improvements in Fire-Injectors and Steam-Superheaters, of which the following is a full, clear, and exact description, reference being had to the accompanying drawings, forming a part of this specification, in which—

Figure 1 represents a side view of my said fire-injector and steam-superheater, and

Figure 2 represents a vertical central section of the fire-chamber, fire-injector, and the shell of the boiler on one side.

To enable those skilled in the art to which my invention belongs to make and use the same, I will proceed to describe it more in detail.

In the drawing, A represents a boiler, to the front of which is attached the fire-chamber B, divided by the fire-grate C. There may be two doors, one, a, through which the fuel is passed to the grate C, and one, b, through which the ashes, cinders, and other refuse matter, can be removed from the ash-pit E. Above the fire-chamber is placed the cylinder F, having a water-space or chamber, c, with which the pipe d, from the upper part of the boiler, communicates. Within the cylinder F works the hollow piston-rod G, to the bottom of which is attached the piston H, which may be packed in the same manner as a steam-piston, or in any other desirable manner.

In the bottom of the cylinder F is a valve, e, having flanges or projections, 1, which strike against the flange 2 when the piston is raised. A pipe, f, leads from the bottom of cylinder F into the boiler A, a ball-valve, 3, being properly arranged in the pipe f, as shown in fig. 2. A pipe, I, also extends from the bottom of cylinder F, down through the fire-chamber, into the ash-pit, the open end being turned up under the grate C, as shown in the drawings.

The operation is as follows: Fire being built or started upon the grate C, the draught is through the smoke-pipe J, which may communicate with a smoke-pipe, K, passing through the boiler A. The piston-rod G, being connected in any proper manner to the working parts of the engine, or shafting turned by the same, is caused to reciprocate, and, when the piston rises, the flame and heated gases from the fire are drawn up into the cylinder F; and, when the piston descends, the fire and gases are expelled, through the pipe f, into the water in the boiler, thus generating steam rapidly, and superheating the steam as they pass up through it.

To facilitate the combustion, and otherwise contribute to the perfect action of the operation, a current of fire and heated gases can be forced from cylinder F, and thrown under the fire, by simply turning cock g. A ball or other valve may be arranged in pipe I, to prevent air from entering the cylinder F, through pipe I, when piston H is raised.

Cylinder F may be arranged, in respect to the boiler, so that the chamber c will be filled with water or steam, as may be preferred, to prevent cylinder F from being heated too much. The piston-rod G may also be connected, by a flexible pipe or otherwise, with a steam or water-chamber, to keep that from being too highly heated.

By removing the stop h, the steam or water in chamber c can be drawn out. Notches are made in the edges of the valve e, to allow the fire and heated gases to pass up into the cylinder F when the piston rises, the valve having a vertical play in the bottom of the cylinder, as indicated in the drawings.

Having described my fire-injector and steam-superheater, what I claim therein as new and of my invention, and desire to secure by Letters Patent, is—

1. The combination, with the boiler or steam-generator and fire-chamber, of a fire-injector and steam-superheater, under the arrangement described, whereby the flame and heated gases shall be taken from the fire-chamber, and forced or driven, under pressure, into the boiler or steam-generator, substantially as herein shown and set forth.

2. The combination, with the cylinder F and fire-chamber G, of the chamber c, piston H, fire-pipes I and f, substantially as and for the purposes set forth.

GEORGE V. SHEFFIELD.
